(57) CLAIM

The ornamental design for a basketball system pole cover, substantially as shown and described.

DESCRIPTION

FIG. 1 is an elevated front perspective view of a basketball system pole cover in accordance with the present invention; FIG. 2 is a front elevation view thereof; FIG. 3 is a rear elevation view thereof; FIG. 4 is a side elevation view thereof; FIG. 5 is another side elevation view thereof; FIG. 6 is a top plan view thereof; FIG. 7 is a bottom plan view thereof; FIG. 8 is a lower rear perspective view thereof; and, FIG. 9 is an elevated rear perspective view thereof. The broken lines illustrate environmental subject matter and form no part of the claimed design. The "SPALDING" lettering and icon forming part of the disclosure is a registered trademark of Russell Brands, LLC.
